W. M. WHEILDON

SECURING THE ENDS OF ROLLS

Filed March 12, 1920

Fig. 1.

Fig. 2.

Fig. 3.

Inventor:
William M. Wheildon,
by Emery, Booth, Farney & Farney,
Attys.

UNITED STATES PATENT OFFICE.

WILLIAM M. WHEILDON, OF ASHLAND, MASSACHUSETTS, ASSIGNOR TO EDWARD H. ANGIER, OF FRAMINGHAM, MASSACHUSETTS.

SECURING THE ENDS OF ROLLS.

Application filed March 12, 1920. Serial No. 365,335.

To all whom it may concern:

Be it known that I, WILLIAM M. WHEILDON, a citizen of the United States, and a resident of Ashland, in the county of Middlesex and Commonwealth of Massachusetts, have invented an Improvement in Securing the Ends of Rolls, of which the following description, in connection with the accompanying drawings, is a specification, like characters on the drawings representing like parts.

This invention relates to the packaging of materials in roll form and has particularly to do with securing the end of the roll in such manner that it may be readily separated when it is desired to use the material. While not limited thereto the invention is more particularly designed for use with rolls of paper strip such, for example, as those used in wrapping tires by machine.

My invention will best be understood by reference to the following description of an illustrative embodiment thereof taken in connection with the accompanying drawings wherein:

Fig. 1 is a side elevation of a roll of paper with its end secured in a manner illustrative of the principles of my invention;

Fig. 2 is an edge view thereof; and

Fig. 3 is a side elevation showing the end separated.

Referring to the drawings I have there shown a roll 5 of paper strip mounted on a core 7. A portion 9 of the outermost turn of the rolled up strip adjacent the end thereof may be turned outwardly or folded back on itself more or less (without necessarily creasing the same) as illustrated in Figure 1, thus providing a projecting tab. In accordance with my invention this tab is sealed to the adjacent body portion of the roll and in the present example this is effected by a separate strip 11 which may consist of a piece of gummed paper tape, preferably weaker and more readily rupturable than the paper which composes the roll 5. This strip 11 may, as in the present example, be folded, but not necessarily creased, so as to present its gummed face both to the inner face of the outermost turn of the material constituting the tab 9 and the outer face of the adjacent inner turn 13 of the roll. Obviously if the part 9 is folded back

sharply the strip 11 will lie substantially flat and vice versa.

The end of the rolled up material is thus securely fastened to the body of the roll and a portion adjacent the end, and conveniently the end itself as here shown, is left free as a tab and may be seized by the fingers as in Fig. 1 when it is desired to start unwinding the material. A pull on the strip will break the more readily rupturable strip 11, as indicated in Fig. 3, leaving the material free to be unrolled. The small portions of the strip 11 which are left adhering to the material may be easily removed, but in most instances they are unobjectionable for purposes to which the rolled material is applied.

Having thus described the embodiment of my invention herein shown by way of illustration, wherein a separate sealing strip is used to secure the end of the roll, the principles exemplified thereby which I claim as new and desire to secure by Letters Patent I shall express in the following claims.

1. A roll of material having its end portion turned back and a separate strip of more readily rupturable material sealed to said turned back portion and the adjacent inner turn of the roll, the end portion of the roll beyond said strip being loosely related to the body of the roll and providing for ready grasping to apply a rupturing tension to said strip.

2. A roll of material having a projecting portion adjacent its end and a folded connecting part relatively weaker than the main portion of the roll sealed to the adjacent turn of the roll and connecting said portion thereto, said projecting portion being loosely related to the body of the roll and providing for ready grasping to apply a rupturing tension to said part.

3. A dispensing package comprising a roll of relatively narrow strip material having a portion adjacent the end thereof loosely projecting as a tab and a folded connecting part sealed to the adjacent turn of the roll closely adjacent said tab and connecting the same thereto whereby the end of the material is conveniently presented for grasping and a natural motion tending to unwind the roll serves to place a rupturing tension on said connection.

4. A dispensing package comprising a roll of relatively narrow strip material having the end thereof projecting as a loose tab, a connecting member sealed to the inner face of the outermost turn of the roll adjacent the end and to the outer face of the next inner turn and providing for said tab a connection to the body of the roll away from the end of the tab, said connection being constructed to break under a strain less than that which would rupture the material of the roll.
5. In testimony whereof, I have signed my name to this specification.

WILLIAM M. WHEILDON.
